UNITED STATES PATENT OFFICE.

WILLIAM M. DAVENE, OF NEW YORK, N. Y.

STAGE-TRAP.

SPECIFICATION forming part of Letters Patent No. 248,639, dated October 25, 1881.

Application filed March 1, 1881. (No model.)

To all whom it may concern:

Be it known that I, WM. M. DAVENE, a citizen of the United States, residing at New York, in the county and State of New York, have invented certain new and useful Improvements in Stage-Traps, of which the following is a full, clear, and exact description, reference being had to the drawings hereto annexed.

My invention relates to stage-traps in which an oscillating board is made to oscillate by means of springs; and its object is to secure safety and ease in applying the springs, and also to limit the degree of force applied, accordingly as may be desired.

My invention consists in providing downward-opening hooks from which the rubber bands may detach themselves as they contract, and a windlass for replacing the bands after the trap is set, and also in providing adjustable stops for limiting the action of the springs, as hereinafter described.

In the accompanying drawings, Figure 1 is a central longitudinal section of a stage-trap embodying my improvements; Fig. 2, a plan view of the same, and Fig. 3 a detail view.

Heretofore stage-traps which employ an oscillating board, in combination with a spring apparatus, have been open to the objection that, unless the springs were weak, the trap could not be set without great difficulty, owing to the fact that the springs were not detachable, and if it was desirable to regulate the degree of force it was necessary to substitute springs of a different degree of elasticity.

To overcome these objections I substitute for the ordinary pivoted frame of the spring apparatus a rigid frame consisting of two parallel inclined bars, C C, suitably attached to the main frame, and having at their upper ends a fixed cross-bar, f, provided with a series of downward-opening hooks on its under or inner side. A cross-bar, d, fitting within the inclined bars C and provided with flanges d' on its upper and lower sides for receiving the said inclined bars and sliding thereon, is connected by a metal loop to the lower end of an arm which is pivoted to the under side of the board B in the ordinary way. This sliding cross-bar is provided on its under or inner side with a corresponding series of downward-opening hooks, upon which endless rubber bands g are loosely secured and expanded, so that they

may also be attached to the hooks on cross-bar f. In case very powerful springs should be used it would be quite difficult as well as dangerous to set the trap as ordinarily constructed. It will be seen, however, that according to my improvement the springs will drop off the hooks when the trap is let fly, and if they are weak they may, after the trap is set, be easily replaced, one by one, by hand. If, on the other hand, the springs are very powerful, they may be expanded and replaced upon the hooks by means of a windlass, k, mounted upon frame A, and provided with a rope and hook for holding the rubber band as it is drawn back.

When it is desired to limit the action of the springs so that the performer will be thrown a given distance the cushioned stops e, which move upon the inclined bars C, may be regulated or adjusted at any desired position by means of pins, whereby the sweep of the cross slide-bar may be lengthened or shortened as desired.

When the trap is to be set the slide d, which has fallen to the lower ends of bars C by the weight of board B, is secured to the tripping-latch h by means of its loop i. This latch is hinged to the side of a block, j, and has a flange, h', which shuts over a wing, h'', hinged to the opposite side of the block, inclosing the loop i underneath, while the upper end of said latch, which has a curved projection, h'', passes through a slot, j', in a rail, m, and is locked by a spring-governed lever, m', on the inner side of said rail. Two perforated ears, m'', attached to this rail on each side of the latch, are designed for receiving a pin to prevent premature or accidental tripping of the latch.

I wish it to be understood that I do not claim a stage-trap consisting of an oscillating lever in combination with springs to cause such lever to oscillate, such a device being shown in a previous patent; but,

Having described the nature of my improvement upon such a stage-trap, I claim as new and desire to secure by Letters Patent—

1. In a stage-trap having an oscillating lever and spring mechanism, two series of downward-opening hooks, one stationary and the other movable, in combination with self-detachable springs, substantially as shown and described.

2. In a stage-trap having an oscillating lever and spring mechanism, two series of downward-opening hooks having detachable springs, in combination with a windlass having a rope and hook, substantially as shown and described.
3. In a stage-trap having an oscillating lever and spring mechanism, the adjustable cushioned stops *c*, in combination with the inclined bars *C*, substantially as shown and described,
- 10 whereby the action of the springs may be limited, as set forth.

4. In a stage-trap having an oscillating lever and spring mechanism, the safety tripping-latch *h*, having flange *h'* and curved projection *h*², in combination with block *j*, wing *h*², slotted rail *m*, perforated ears *m*³, and lever *m'*, substantially as shown and described. 15
